UNITED STATES PATENT OFFICE.

CHRISTENA MURPHY, OF NEW YORK, N. Y.

COMFORT CUSHION.

Application filed May 8, 1926. Serial No. 107,577.

This invention relates to improvements in comfort cushions, and has particular reference to such cushions as may be used in conjunction with bed pans for invalids.

5 An important object of the invention is to provide a yieldable cushion for use with bed pans, and of such form and proportions as to comfortably support the lower portion of the back of a person using the same in a reclining position.

Another object is to provide such a device which can be used in either a reclining or a sitting posture, and which may be easily cleaned and maintained in a sanitary condition.

15 Another object is to provide such a device in detachable sections whereby to facilitate its use in various environments and conditions, and to render it more readily portable.

20 Other objects and advantages will be apparent from the following description and the accompanying drawings, wherein a preferred embodiment of the invention is shown by way of illustration, and wherein,

25 Figure 1 is a vertical longitudinal sectional view taken on the line 1—1 of Figure 2, and showing a cushion embodying the invention in association with a bed pan;

Figure 2 is a top plan view of the device; 30 Figure 3 is a detail perspective view of one of the cushion members, and

Figure 4 is a similar view of the other cushion member detached from the first cushion.

35 In carrying out the invention, a cushion is formed with a main body portion 10 and an overhanging portion 11 at one edge thereof. Preferably the portions 10 and 11 are separately and provided with means for detachably securing them together, although they may, if desired, be formed integrally.

The main body portion 10 of the device illustrated in the drawings is a complete cushion, in itself having a bottom wall 12, top wall 13, edge walls 14 and 15, and side walls 16, properly joined together in any manner known to those skilled in the art. The material of which the cushion is formed must be yieldable and preferably of a waterproof character, and preferably sheet rubber is used for this purpose. In order to vary the yieldability of the cushion 10, it is hollow, and one of its side walls 16 is fitted with a pneumatic check valve 17 by means of which the cushion may be inflated as desired. The invention is not necessarily restricted to a

pneumatically inflated cushion since it might be upholstered in any suitable manner if desired.

As shown in Figures 1 and 2, the cushion 10 is adapted to be disposed laterally of a bed pan 18, with its edge wall 14 preferably against the head end 19 of the pan. The wall 14 is slightly higher than the pan, and the top wall 13 slopes downwardly to the wall 15, which is disposed toward the head of a person using the device in a reclining position, for example an invalid. A flap portion 21 is provided on the upper wall 13 adjacent to said highest edge 14, said flap portion defining a pocket 22 within which are a plurality of fastening elements 23, of any ordinary or preferred form.

The portion 11 of the bed pan cushion is also preferably formed of waterproof material, preferably elastic, and is provided with a straight side edge 24 for disposition toward the edge wall 14 of the member 10, and having its opposite edge 25 concave, whereby the member will have the general configuration of a crescent with enlarged end portions 26. This member is also preferably hollow and fitted with a check valve 27 similar to the valve 17. A pair of tongues 28 extend laterally from the side edge 24 and are adapted to be disposed within the pocket 22 of the cushion 10, and each tongue 28 being provided with a fastening element 29 for detachable engagement with the elements 23 within the pocket.

When the device is to be used by an invalid in a reclining position, the two portions 10 and 11 are attached together by means of the fasteners 23 and 29, and after being inflated to the desired degree, are put in place under the invalid, the portion 10 supporting the lower portion of the invalid's back, and the other portion 11 overlying the rim 20 of the bed pan 18. When the cushion members are formed hollow and inflatable as described, the degree of inflation may be varied in accordance with the weight, sensitivity, etc., of the person using it. It is obvious also that the device may be used in a sitting posture, in which case the cushion member 11 may be entirely detached from the portion 10, and used independently.

From the foregoing it will be evident that an improved comfort cushion has been provided which will effectively and comfortably support the lower portion of the back of an invalid when using a bed pan, thus overcom-

ing the unpleasantness and discomfort incident to the use of such devices in the past. The formation of the complete device from detachable sections renders it readily portable and capable of being stored in a minimum space. Furthermore, by forming the parts of sheet rubber or some equally waterproof material, the cushion may be maintained in a sanitary condition by washing or sterilizing without injury to the same.

Obviously the invention is susceptible of modifications in the details of construction and arrangement of parts, and the right is herein reserved to make such changes as fall within the scope of the appended claims, without departing from the spirit of the invention.

Having thus described my invention, what I claim, is:

- 20 1. A comfort cushion, for use with a bed pan, and including a pair of cushion sections assembled together, one of said sections being thicker than the other and adapted to be positioned laterally of a bed pan at the upper edge thereof, and the other section being adapted to overlie a portion of the rim of the bed pan.
- 25 2. A comfort cushion, for use with a bed pan, and including a pair of cushion sections assembled together, one of said sections being thicker than the other and adapted to be positioned laterally of a bed pan at the upper edge thereof, and the other or thinner section being substantially crescent shaped to overlie a portion of the rim of the bed pan, and being formed with a sanitary cover.
- 30 3. In a device of the character described,

the combination with a cushion adapted to support the lower region of the back of a person in reclining position, a substantially crescent shaped cushion of less thickness than the first cushion, said crescent shaped cushion being adapted to overlie portions of a bed pan placed adjacent the first cushion, and means for detachably connecting said cushions together.

4. In a device of the character described, the combination with a cushion adapted to support the lower region of the back of a person in reclining position, a substantially crescent shaped cushion of less thickness than the first cushion, said crescent shaped cushion being adapted to overlie portions of a bed pan placed adjacent the first cushion, said cushions being formed of elastic material and being inflatable to any desired degree of resiliency, and means for detachably connecting said cushions together.

5. In a device of the character described, the combination of a cushion having a sloping upper surface, a pocket with a cover flap formed on the upper surface adjacent the highest edge thereof, and having fastening elements within the pocket, a second cushion of less thickness than the first mentioned cushion and extending laterally from the highest edge of said sloping upper surface, said second cushion having fastening elements adapted to extend into the pocket for engagement with those in said pocket, and the opposite edge of the second cushion being inwardly curved substantially as set forth.

CHRISTENA MURPHY.
